AIR-CONDITIONING APPARATUS OF THE INDUCTION TYPE

Luigi Chieregatti, Milan, Italy

Application July 1, 1958, Serial No. 746,030

Claims priority, application Italy August 23, 1957

2 Claims. (Cl. 62—296)

This invention relates to an air-conditioning apparatus of the induction type.

Air-conditioners of the induction type comprise a primary air supply chamber to which air flows at high speed and high static pressure from a fan, if desired in a pre-conditioned state, air flowing from the supply chamber through a valved opening to silencing and expansion chamber provided on a wall thereof with injection nozzles. The primary air enters through the nozzles at high speed a mixing chamber and induces from the surroundings through a heat exchanger extending along said mixing chamber a secondary air stream with which it forms a mixture which is supplied through a port to the room to be conditioned.

The main object of this invention is to provide an air-conditioner of the type referred to above, improved to combine a satisfactory operation and inexpensive installation, low cost of manufacture and moderate height, whereby it is suitable for installation below the windows of modern buildings with low sills.

An object of this invention is to provide a special arrangement of the supply chamber, silencing and expansion chamber and mixing chamber.

In conventional apparatuses the supply and expansion chambers are mostly vertically superposed to provide an apparatus of moderate width, which is, however, of considerable height and unsuitable for installation in rooms with modern glazings and low sills.

In the improved apparatus the above mentioned drawback is removed by arranging the supply chamber and silencing and expansion chamber side by side in horizontal direction in a lower portion of the apparatus, thereby forming a box of approximately rectangular cross-sectional shape which, when the apparatus is hung to a wall or placed on the floor, has its longer side extending parallel to the floor. The mixing chamber is situated at the middle of the top portion of the apparatus, leaving two lateral regions free. The latter enclose the heat exchanger facing the front of the apparatus and fluid pipes supply the heat exchanger accommodated by a recess facing the back of the apparatus.

In addition to efficiently reducing the overall size of the apparatus in a transverse direction, the improved arrangement is advantageous, inasmuch as it permits, more particularly with a plurality of apparatuses in a side-by-side arrangement, full freedom in securing to the wall the supply pipes for the heat exchangers and arranging in said pipes the taps for the various apparatuses which are then placed in front of the pipes assembled and insulated.

Such arrangement of the supply pipes for the heat exchangers is further advantageous in that it avoids laying said pipes in the floor or ceiling where the pipes would hardly be accessible and a useful space would be lost in a vertical direction for disguising the pipes.

A further characteristic feature of the improved apparatus resides in the use of the heat exchanger of small height, preferably not exceeding 20 cm., without detri-

2

mentally reducing its front area and heat exchange surface, the heat exchanger being therefore, its front area being the same, greater in length than present constructions.

5 In addition to limiting the height of the apparatus, its induction ratio is thereby improved over apparatuses of the same exchange surface area arranged on a smaller length and greater height.

The primary air volume and front area of the heat 10 exchanger being the same, the improved apparatus affords a heat exchanger of reduced height having, with respect to conventional apparatuses with a heat exchanger of greater height, an improved induction ratio, that is an improved ratio of induced air to primary air, for the 15 following reasons:

(1) The primary air quantity per unit of length of the heat exchanger is reduced.

(2) The contact surface between the primary air and induced air is increased through the possibility of increasing the number of nozzles.

(3) The spacing of nozzles can be increased within certain limits.

The secondary air volume is further increased because the heat exchanger of greater length and smaller height 20 increases the available area for the flow of secondary air at the region nearest the nozzles, at which the induction effect is greatest.

A further object of this invention is to arrange the 25 nozzles and heat exchanger on a wall sloping towards the room through an angle of 5 to 15° to the horizontal. The injection nozzles and heat exchanger are mounted in parallel relationship, their axes being perpendicular to said wall, so that they are inclined forwardly towards the room through 5 to 15° to the vertical. This results 30 in air mixture issuing from the apparatus which is spontaneously forwardly directed towards the room, thereby enhancing the air circulation in the room and removing from the surroundings of the window, tapestry regions and like the conditioned air lamination; without resorting 35 to a set of longitudinal baffle wings which have to be provided on the outlet port in present conditioners in which, the nozzle axes extending in a vertical plane the conditioned air lamination tends to issue in a vertical direction.

40 The wall carrying the nozzles and to which the heat exchanger is attached, extends forwardly beyond the heat exchanger to form a sump connecting and discharging any condensate from ambient moisture which might be formed as a result of improper operation of the plant. 45 This sump is therefore situated at a freely accessible region outside the heat exchanger on the front of the apparatus, the water collecting therein by dripping along the inclined wall.

The drawbacks of conventional apparatuses in which 50 the sump for the condensate is situated beneath the heat exchanger are thereby eliminated, said drawbacks consisting in that the sump is difficult to clean, the exchanger plate ends which, with a considerable condensation, are submerged in water are liable to oxidize, the re-evaporation being hardly possible in that the re-evaporation surface is partly screened by the overlying heat exchanger. The improved apparatus affords an extensive re-evaporation surface which is fully exposed and will not in any case involve the plates on the heat exchanger which are 55 therefore constantly kept dry. The extensive re-evaporating surface will in most cases make the condensate discharge system superfluous.

The slope of the wall carrying the nozzles and heat 60 exchanger leaves between the heat exchanger and suction strainer for the secondary air a triangular space free, which is usefully employed for arranging the air filter

and thermostat valve, thereby avoiding the necessity of increasing the depth of the conditioner.

A further feature of this invention resides in that the passage between the primary air supply chamber and silencing and expansion chamber is located at the lower portion of the partition between both chambers, said passage extending throughout the length of the apparatus. The passage extending throughout the length of the apparatus allows of air displacement from its inlet into the silencing and expansion chamber up to the nozzle plane at very low rate of speed free from longitudinal delivery currents. This circumstance as well as the arrangement of the air passage at the lowest portion of the partition between the high and low pressure chambers, hence most remote from the nozzles, permits of arranging in the expansion chamber an excellent extensive silencing labyrinth, through which air moves evenly without swirling, this insuring a thorough noislessness and a highly uniform form delivery beneath the nozzle plane.

Further characteristic features and advantages of this invention will be easily understood from the appended description which refers to the accompanying drawings showing a preferred embodiment of the invention given by way of example only. On the drawings:

Figure 1 is a perspective view of the apparatus.

Figure 2 is a longitudinal section of view of the apparatus on line II—II of Figure 3.

Figure 3 is a cross-sectional view of the apparatus on line III—III of Figure 2.

Figure 4 is a part cross-sectional view of the apparatus showing a further embodiment of the silencing labyrinth.

Figure 5 is a detail view of a plate of the heat exchanger and

Figure 6 is a cross-sectional view of the heat exchanger plate.

The air-conditioner shown in Figures 1 to 3 comprises a basic body including the supply chamber 1, control valve 2, silencing and expansion chamber 3 extending adjacent the chamber 1 in the lower portion of the apparatus, injection nozzles 4, mixing chamber 5, heat exchanger 6 with automatic or manually operated adjusting valve 7 therefor and air filter 8. The apparatus is completed by a cabinet comprising a frame 9 having a laterally off-set top lid 10, a front panel 11, an inlet strainer 12 and an outlet strainer 13.

The apparatus shown in Figures 1 to 3 can be encased in either a vertical or horizontal position, the covering including appropriate encasing structures provided with strainers 12 and 13.

The primary air flows to the supply chamber 1 through a hose 39 connected with a central conditioning station, reaches the silencing and expansion chamber 3 through the adjusting valve 2 and passage 14 which, according to this invention, is situated in the lower portion of the chamber and extends throughout the length thereof. The primary air reaches through the silencing labyrinth, established by the baffles 15, the injection nozzles 4 through which it is injected in the mixing chamber 5 in which it induces from the surrounding through the inlet strainer 12, filter 8 and heat exchanger 6 a secondary air stream with which it becomes mixed, the mixture issuing through the outlet strainer 13 to the room to be conditioned.

The silencing labyrinth 15 is formed by one horizontal and two vertical baffle sections extending throughout the length of the chamber, the air therein being twice deflected through 90° and twice deflected through 180°.

In the modification shown in Figure 4 the silencing labyrinth is formed by three horizontal baffles causing the air to be deflected three times through 180°.

According to this invention the chambers 1 and 3 extend lengthwise parallel with each other in a horizontal plane at the lower region of the apparatus. The mixing chamber likewise extends longitudinally in the middle region of the upper portion of the apparatus. The heat

exchanger is of small height preferably not exceeding 20 cm.

The wall 16 carrying the injection nozzles 4 is inclined to the horizontal through an angle α , the slope amounting to 5 to 15°. In addition to the nozzles the wall 16 carries a seating for the heat exchanger and forms by an extension towards the front the sump 17 collecting the condensed water. Both, nozzles 4 and heat exchanger 6, which extend parallel with each other and perpendicular to the slope 16, are inclined through angle α to the vertical.

The control valve 2 comprises a valve member 18 which can be calibrated by means of a calibrating device designated as a whole by 19, which becomes accessible upon removal of the strainer 13 through the top opening in the mixing chamber 5, so as to adjust the static pressure beneath the nozzles plane, hence the inflow of primary air to the nozzles. A remote control 24, which is easily fitted to the left or right of the apparatus serves for closing or opening the valve upon opening of the lid 10 on the frame 9 beside the outlet strainer 13. Through the lid the adjusting valve for the heat exchanger and its control, in the case of a manual control, or the thermostat, in the case of an automatic valve, are also accessible. In this case, the thermostat valve 34 is arranged in the triangular clearance between the inlet strainer 12 and heat exchanger 6.

The valve member 18 and control and calibrating means therefor are disclosed in a copending application Ser. No. 745,931 filed July 1, 1958 by the same applicant.

Figures 5 and 6 show in plan and sectional view, respectively, a detail of the plates of the exchanger 6. The plates are formed with ribs 38 adapted to increase both the plate surface and turbulence of air through the exchanger, thereby improving heat exchange.

Figure 2 shows the special arrangement of the side walls 31 which close the lower portion of the apparatus enclosing the supply and expansion chambers. The side walls are retracted with respect of the extreme end sections of the heat exchanger and leave two clearances free in which it is possible to arrange, without increasing the overall length of the apparatus, pipes 32 for connection, if desired, of the sum 17 to the discharge system and device 33 for levelling the apparatus on installing on the floor or to the wall.

Figures 1 to 3 further show the special construction of the cabinet frame 9. The frame has a longitudinal plane of symmetry (Fig. 3) and can therefore be assembled to easily carry out an apparatus with a lid for the control of the adjusting valves for the heat exchanger and primary air on the left or right side respectively.

It will be understood that embodiments and constructional details can be varied from the example described and shown within the principle of this invention without departing from the scope thereof.

What I claim is:

1. In an air conditioning apparatus of the induction type a horizontally elongated air box of a substantially rectangular cross-sectional shape, a mixing chamber overlying the air box, a longitudinally extending partition in the air box subdividing the interior of the latter into a plenum chamber and a silencing-expansion chamber, the last named chambers being vertically co-extensive in the box and being arranged in a mutual side-by-side relationship, a valve-controlled primary air passage from the plenum chamber to the silencing-expansion chamber extending through the said partition lengthwise thereof, a plurality of baffles extending in the silencing-expansion chamber lengthwise of the latter whereby, when seen in cross-sectional view, the silencing-expansion chamber is of a labyrinth shape, and primary air nozzle means connecting the labyrinth with a bottom section of the overlying mixing chamber.

2. In an air conditioning apparatus of the induction type a horizontally elongated air box of a substantially

rectangular cross-sectional shape, a mixing chamber overlying the air box, a longitudinally extending partition in the air box subdividing the interior of the latter into a plenum chamber and a silencing-expansion chamber, the last named chambers being vertically coextensive in the box and being arranged in a mutual side-by-side relationship, a primary air passage from the plenum chamber to the silencing-expansion chamber extending through the said partition lengthwise of the latter, a valve member for controlling the said primary air passage arranged in the plenum chamber, a plurality of baffles extending in the silencing-expansion chamber lengthwise of the latter

whereby, when seen in cross-sectional view, the silencing-expansion chamber is of a labyrinth shape, and primary air nozzle means connecting the labyrinth with a bottom section of the overlying mixing chamber.
